[57] **CLAIM**

The ornamental design for a dental burr holder, substantially as shown.

DESCRIPTION

FIG. 1 is a perspective view taken from the top, front and left side of a dental burr holder showing my new design;

FIG. 2 is a top plan view thereof;

FIG. 3 is a left side elevational view thereof, the right side being substantially a mirror image thereto;

FIG. 4 is a front elevational view thereof;

FIG. 5 is a rear elevational view thereof; and

FIG. 6 is a bottom plan view thereof.
